FIG.5

FIG. 6

FIG. 7

FIG. 1 is a front perspective of a printer console embodying the invention.

FIG. 2 is a perspective drawing taken from the rear showing the design of FIG. 1.

FIG. 3 is a plan view of the design shown in FIG. 1.

FIG. 4 is a front elevation of the design shown in FIG. 1.

FIG. 5 is a rear elevation of the design shown in FIG. 1.

FIG. 6 is a side elevation taken from the left of the printer console shown in FIG. 1.

FIG. 7 is a side elevation taken from the right side of the printer console shown in FIG. 1.

We claim:

The ornamental design for a printer console, as shown.
